UNITED STATES PATENT OFFICE

WILLIAM C. EPSTEIN, OF DAYTON, OHIO, ASSIGNOR TO THE DUO-TOR MANUFACTURING COMPANY, OF DAYTON, OHIO, A CORPORATION OF OHIO

COMBINED WATER HEATER AND INCINERATOR

Application filed June 15, 1927. Serial No. 198,892.

This invention relates to a combined water heater and incinerator.

One object of the invention is to provide such a combined structure which will be simple in its construction, efficient in its operation, and compact in form.

A further object of the invention is to provide such a combined heater and incinerator having a water heating coil, and means whereby said coil may be cleaned or delimed without removing it from the structure; and from which the coil may be easily removed for repair or replacement.

A further object of the invention is to provide such an apparatus with means for regulating the draft therethrough.

Other objects of the invention will appear as the device is described in detail.

In the accompanying drawings Fig. 1 is a vertical sectional view taken centrally through an apparatus embodying my invention; Fig. 2 is a transverse sectional view taken on the line 2—2 of Fig. 1; Fig. 3 is a sectional detail view showing the means for 25 mounting the coil and for cleaning the same; Fig. 4 is a transverse section taken on the line 4—4 of Fig. 3; Fig. 5 is a transverse section taken on the line 5—5 of Fig. 1; Fig. 6 is a vertical sectional view taken centrally through a slightly modified form of the apparatus; Fig. 7 is a vertical sectional view taken centrally through another form of the apparatus and partly broken away; and Fig. 8 is a transverse section taken on the line 8—8 of 35 Fig. 7.

In these drawings I have illustrated certain embodiments of my invention but it will be understood that these embodiments have been chosen for the purposes of illustration only 40 and that the several parts may take various forms and arrangements without departing from the spirit of the invention.

In that particular embodiment shown in Figs. 1 to 5, the apparatus comprises a water heating tank 1 having an opening there-

through forming a combustion chamber within which the garbage, or other material to be incinerated, may be supported in such a manner that the same flame which heats the water will consume the garbage. As here shown, 50 the tank is annular in cross section and the inner wall 2 thereof constitutes the wall of a central opening within which the material to be incinerated may be supported. The tank may be mounted in any suitable manner, as 55 upon legs or standards 3. Communicating with the tank is a cold water supply pipe 4 and a hot water outlet pipe 5. In the present construction both pipes are connected with the tank through the top wall thereof and the supply pipe 4 extends to a point near the bottom of the tank. 60

The means for supporting the garbage within the tank may take various forms and in that form of the device shown in Figs. 1 65 and 2, I have provided a separate hopper or receptacle 6 which is arranged within the opening in the tank and supports the garbage therein. This hopper as here shown is substantially cylindrical for the greater part 70 of its length but has its upper end flared or enlarged, as shown at 7, to facilitate the introduction of the garbage into the same. Preferably it is readily removable from the tank and to this end it is supported wholly 75 at its upper end. As here shown, the tank is provided with a top casting 8 which extends about the upper end of the opening therethrough and has a central opening in line with the opening through the tank. This 80 top casting also has an inwardly extending annular flange 9. Removably supported on the flange 9 of the top casting is an annular supporting member or ring 10, the circumferential portion of which rests upon the flange 9, and which has a downwardly extending flange 11, to which the upper end of the hopper is secured. The arrangement is 85 such as to provide a tight joint between the supporting member 10 and top casting, and 90

a removable closure 12 rests upon the supporting structure and embraces an annular rib or upwardly extending flange 13, so as to tightly close the top of the hopper. The 5 lower end of the hopper is provided with a perforated bottom wall or grate 14 and the lower portion of the side wall thereof is slotted, as shown at 15. The hopper is of a diameter considerably less than the internal 10 diameter of the inner wall 2 of the tank, thus providing between the hopper and the tank a space or passageway for the products of combustion. The top casting 8 has an outlet 16 through which the products of combustion 15 may escape to a pipe 17 which leads to the flue.

Arranged beneath the hopper is a burner 18, which is here shown as annular in form, having an imperforate top wall and having 20 inner and outer circumferential slots 19 and 20 through which the gas may escape and from which the flame will rise. The top wall has at its outer edges depending flanges 18^a which overlap but are spaced from the respective slots 19 and 20, so as to permit the escape of gas but to prevent foreign material from entering the slots and clogging the same. It will be noted that the arrangement of the burner is such that the jet of flame from the 25 inner slot 19 will rise against the bottom of the hopper while the jet of flame from the outer slot 20 will rise into the passageway between the hopper and the tank. The burner is connected with a fuel supply pipe 21 in 30 which is inserted an automatic valve 22, a pilot burner 23 being provided and connected with the supply pipe on the outer side of the valve 22. A thermostat 24 extends into the tank and is operatively connected with the 35 automatic valve. The automatic valve and its controlling thermostat may be of the usual or any suitable construction and inasmuch as these devices form no part of the invention, aside from their combination with the other 40 parts thereof, it is not necessary to illustrate or describe the same in detail.

It will be apparent that in the operation of the device the valve 22 will be opened when the temperature of the water within the tank falls to a predetermined degree and that the burner will continue to operate until the temperature of the water has risen to a higher predetermined degree, at which time the thermostat will operate to close the 50 valve. Thus the temperature of the water will be automatically maintained between such minimum and maximum degrees. When the burner is in operation any garbage within the hopper will be subjected to the action of the flame and will be consumed. It is not essential that all the garbage which is in the hopper should be consumed at one 55 operation of the burner but the quantity may be such that it will require several operations of the burner to entirely consume the same.

There is usually a definite relation between the amount of garbage accumulated in the kitchen and the amount of hot water used and consequently the burner will usually operate for a sufficient length of time to consume the garbage which has accumulated. As has been stated, however, this is not essential and even should no hot water be used the burner will come on periodically, because of the lowering of the temperature of the water in the tank due to radiation, and the successive operations of the burner will cause the incineration of the garbage in the hopper. 70

In some installations, and more particularly in the larger units, it may be desirable to provide a water heating coil through which the water in the tank may circulate and which will facilitate the heating of the water. In Figs. 1 and 2 I have shown such a coil, at 25, as arranged in the passageway between the hopper and the inner wall of the tank, the coil having open communication at its upper and lower ends with the interior of the tank and being arranged directly in the path of the products of combustion in the passageway. In the present instance, I have shown this heating coil as a duplex coil, that is, it comprises two parallel pipes connected one to the other at their ends only. Such a coil results in a more uniform heating of the water in the tank and prevents the creation of an excessive temperature at the top of the tank before the temperature in the lower portion of the tank rises sufficiently to cause the thermostat to close the valves. Heating coils 95 will sometimes become clogged up with foreign matter or lime, this being particularly true when hard water is being heated, and it is necessary to clean or delime the coil. In the present construction, I have provided means whereby a cleaning fluid, or acid, may be passed through the coil to delime the same without removing the coil or dismantling the apparatus. To accomplish this I have connected with the upper and lower ends of the coil, respectively, fittings 26 and 27, which are arranged within the tank in line with openings in the outer wall thereof, said openings being normally closed by plugs or caps 100 28 which, when removed, permit access to be had to the fittings. 105

One form of the fitting and one manner of securing the same to the coil is shown in Fig. 3, and inasmuch as the construction is the same at both ends of the coil it will be necessary to describe but one fitting and its connection with the coil. As shown in the drawing the end of the coil is connected with a coupling member 29 which, in the present instance, is of such a size as to receive the ends of the two members of the duplex coil. This coupling member has a screw threaded opening 30 and is provided about that opening with a flange 31 having a concave contact surface or seat 32. Rigidly secured to the 110 115 120 125 130

inner wall 2 of the tank, as by welding, in line with an opening therein, is a collar 33 having an internal screw thread 34. Screw threaded into this collar is a second coupling member 35 having on its inner end a head 36 which is provided with a convex contact surface to engage the contact surface 32 of the coupling member 29. Any suitable means may be provided for rotating the coupling member 35 to adjust it in the collar and, as here shown, this coupling member is provided with two inwardly extending lugs 37 adapted to be engaged by the edges of the bar inserted therein through the opening in the outer wall 15 of the tank. The fitting 26 is in the form of an elongated tube or conduit of such an external diameter that it will extend through the coupling member 35 and this tube has its inner end screw threaded to enter the threaded opening in the coupling member 29. At a point spaced from the screw threaded end thereof the fitting has a circumferential flange 38 to bear against the adjacent edge of the collar 33. Preferably this flange has an annular recess to receive a packing ring 39 which engages the edge of the collar. By inserting the fitting through the coupling member 35 and screwing it into the coupling member 29, the contact surfaces of the two coupling members may be brought into sealing contact and the sealing ring 39 of the fitting may be pressed tightly against the collar 33, thus providing a rigid support for the end of the coil and establishing a tight joint between the same and the fitting. Any suitable means may be provided for rotating the fitting, such as inwardly extending lugs 40 adapted to be engaged by the edges of a bar inserted through the outer wall of the tank. The end of the fitting is here shown as arranged close to the cap 28 in the wall of the tank and to permit of the free circulation of water through the fitting I have provided the same with slots 41. The outer slotted portion of the fitting is of a diameter slightly greater than the inner portion thereof and this inner portion, adjacent to the slotted portion, is screw threaded as shown at 42, to adapt it to receive the end of a conduit or pipe which may be inserted through the opening in the outer wall of the tank and which provides the means for introducing cleaning fluid through the fitting into the coil, or withdrawing the same therefrom. The conduits or pipes used for this purpose may be of any suitable character, as shown at 43 and 43^a, respectively, in Fig. 1. Preferably the conduit at the upper end of the coil is provided with a funnel-shaped portion or is adapted to receive a funnel to facilitate the introduction of the cleansing fluid into the fitting. The conduit or pipe at the lower end of the coil may be provided with a valve 44 to enable the liquid to be retained in the coil for the desired length of time.

This manner of mounting the coil not only permits of the passing of the cleansing fluid through the same while it is in position but also enables it to be quickly and easily removed from the tank for the purpose of repairing or replacing the same. To remove the coil it is only necessary to remove the hopper and to then remove the caps 28 and unscrew the fittings 26 and 27, thereby releasing both ends of the coil and permitting the same to be lifted out of the tank. 70 75

In order that the draft through the apparatus may be regulated I have interposed in the pipe 17 a device which is here shown in the form of a frusto-conical housing 45, 80 the smaller upper end of which merges into the pipe and the larger lower end of which has a bottom wall 46 provided with a central opening with which the upper end of the lower section of pipe is connected. This bottom wall, between the pipe 17 and the outer wall of the housing, has a circumferential series of openings 47 which are controlled by a rotary damper 48. As here shown, this damper is in the form of a plate 90 arranged beneath the bottom wall 46 and having a series of openings 49 which may be moved into and out of registration with the openings 47 in the bottom plate, thus permitting more or less air to enter the pipe 95 and thereby regulating the draft through the apparatus. The damper may be mounted on the housing in any suitable manner but, as here shown, the bottom wall 47 extends slightly beyond the outer wall of the housing and forms a flange 50 and the outer portion of the annular plate or damper 48 is bent upwardly and inwardly to form a guide-way 51 which embraces this flange and rotatably supports the damper in close contact with the bottom of the housing. A handle, as shown at 52, may be attached to the damper for the purpose of adjusting the same. Mounted within the housing 45, between the upper and lower ends thereof, is 100 an inverted cone 53 which is supported by arms 54 attached to the wall of the housing. This cone is of a diameter slightly greater than the diameter of the opening in the bottom wall 46 and serves to interrupt or retard 110 any downdraft through the smoke pipe, without interfering with the free passage of the products of combustion through the housing. 115

In Fig. 6 I have shown a slightly modified arrangement of the apparatus, omitting the heating coil. As there shown, the tank 55 is similar in shape to that above described and a burner 56 is also similar in its arrangement and control to the burner shown in Fig. 1, 120 the automatic controlling mechanism not being shown in this figure. The hopper 57 is carried by a supporting member 58 which rests upon the top casting 59. This hopper has a perforated bottom wall 60 and the 130

lower portion of the side wall thereof is slotted, as shown at 61. The diameter of the hopper is such as to leave a relatively small space or passageway between the same 5 and the inner wall 62 of the tank and it is provided above the perforated portion thereof with a spiral rib 63, which partially obstructs the passageway and which causes the products of combustion to circulate about 10 the hopper and thus more fully utilizes the heat.

In Figs. 7 and 8, I have shown another form of the apparatus which also comprises a tank 64 which is annular in cross section 15 and in which the inner wall 65 of the tank constitutes in part a receptacle for the garbage to be consumed. The lower portion of the opening through the tank is of greater diameter than the upper portion thereof, as 20 shown at 66, and the inner wall 65 of the upper portion of the tank has an extension 67 which projects downwardly into the larger portion of the opening, this extension being provided with a perforated bottom 68 and 25 a slotted side wall, as shown at 69. Thus it constitutes in effect a basket which is arranged directly above the burner 70. Preferably this basket is removably secured to the lower end of the wall 65, as shown at 71, 30 so that it can be removed for the purpose of repairing or replacing the same. A top casting 72 and a supporting ring 73, similar to those above described, are provided and secured to the supporting ring 73 is a tapered 35 structure or chute 74, which extends into the opening formed by the inner wall 65 of the tank and serves to guide the material or garbage into the same, this chute being provided with a series of openings 75 to permit 40 the gases to escape therefrom. In order that the products of combustion may pass upwardly through the tank and may contact with relatively large portions of the surface thereof, the tank is provided about the inner 45 wall 65 thereof with a series of passageways 76 which extend from the enlarged portion of the opening therethrough to the top casting where they are connected with the outlet 77. These passageways are here shown in 50 the form of substantially rectangular inserts in the tank but obviously they may comprise pipes or may be of any suitable character.

While I have shown and described certain embodiments of my invention I wish it to be understood that I do not desire to be limited to the details thereof as various modifications may occur to a person skilled in the art.

Having now fully described my invention, what I claim as new and desire to secure by 60 Letters Patent, is:

1. In a combined incinerator and water heater, a tank having inner and outer walls spaced one from the other to form a water receptacle between them, a hopper supported within and spaced from said inner wall, a

burner arranged beneath said hopper, a water coil arranged about said hopper, a coupling member attached to one end of said coil and having a screw threaded opening, a second coupling member mounted on the inner wall of said tank, a fitting communicating with said water receptacle, extending through said second coupling and having a screw threaded portion to engage the opening in the first mentioned coupling member and adapted to draw said first mentioned coupling member into sealing contact with said second coupling member, the outer wall of said tank having an opening adjacent to said fitting, and a removable closure for said opening. 70

2. In a combined incinerator and water heater, a tank having inner and outer walls spaced one from the other to form a water receptacle between them, a hopper supported within and spaced from said inner wall, a burner arranged beneath said hopper, a water coil arranged about said hopper, a coupling member attached to one end of said coil and having a screw threaded opening, the inner wall of said tank having an opening adjacent to said coupling member, a collar rigidly secured to said inner wall and extending about said opening, a second coupling member carried by said collar, a tubular member arranged within said water receptacle, extending through said collar and said second coupling member and having screw threaded engagement with the first mentioned coupling member and also having a shoulder arranged to have contact with said collar, whereby the rotation of said tubular member will draw said coupling members into contact one with the other and will cause said shoulder to engage said collar, the outer wall of said tank having an opening in line with said tubular member, and a removable closure for said opening, said tubular member having a screw threaded portion to receive a conduit inserted through the opening in said outer wall. 90

3. In a combined incinerator and water heater, a tank having inner and outer walls spaced one from the other to form a water receptacle between them, a hopper supported within and spaced from said inner wall, a burner arranged beneath said hopper, a water coil arranged about said hopper, coupling members connected respectively with the upper and lower ends of said coil, tubular members mounted in the inner wall of said tank, extending into said water receptacle and connected respectively with the coupling members at the opposite ends of said coil, the outer wall of said tank having openings adjacent to the respective tubular members, and removable closures for said openings, said tubular members having threaded portions to receive conduits inserted through the respective openings in the outer wall of said tank. 110

4. In a combined incinerator and water heater, a tank having inner and outer walls 115

- spaced one from the other to form a water receptacle between them, a hopper supported within and spaced from said inner wall, a burner arranged beneath said hopper, a water 5 coil arranged about said hopper, coupling members secured to the respective ends of said coil, other coupling members mounted in the inner wall of said tank, tubular members arranged within said water receptacle, extending through the last mentioned coupling members and having screw threaded engagement with the first mentioned coupling members to cause the latter to operatively engage the last mentioned coupling members and to 10 support the respective ends of said coil, the outer wall of said tank having openings in line with said tubular members, and removable closures for said opening.
5. In a combined incinerator and water 20 heater, a tank comprising inner and outer walls spaced apart to form a water receptacle between them, a hopper arranged within said inner wall and spaced therefrom, a burner arranged beneath said hopper, a water coil arranged about said hopper and comprising parallel pipes wound about said hopper, tubular members arranged within said tank extending through the inner wall thereof adjacent to the upper and lower ends of said 25 coil, and means for connecting both pipes of said coil at their upper and lower ends with the respective tubular members.
6. In a combined incinerator and water heater, a tank having a combustion chamber 30 and a passageway opening through the upper and lower ends thereof and surrounded by said tank, means to support material to be consumed in said combustion chamber, and a burner arranged beneath said combustion chamber and said passageway, said passageway being arranged to conduct products of combustion about said material and in contact with the wall of said tank.
7. In a combined incinerator and water 35 heater, a tank, a receptacle arranged within said tank to receive material to be incinerated, and a burner beneath said receptacle, said tank having a passageway for products of combustion extending through said tank outside of said receptacle from a point adjacent to said burner to a point near the top of said tank and so arranged that the products of combustion passing through the same will come in contact both with said receptacle 50 and with the inner wall of said tank.
8. In a combined incinerator and water heater, a tank comprising inner and outer walls arranged to form a water receptacle between them and to form a combustion chamber within said inner wall, a receptacle for material to be incinerated arranged within said combustion chamber and spaced from said inner wall to form a passageway for 55 products of combustion between said recepta-
- cle and said inner wall, and a burner arranged beneath said second mentioned receptacle.
9. In a combined incinerator and water heater, a tank having an inner wall arranged to form a combustion chamber within said tank, a burner supported adjacent to the lower end of said combustion chamber, means to support material to be incinerated within said combustion chamber and above said burner, and a hollow structure extending about and communicating with the upper end of said combustion chamber and having an outlet for products of combustion, said tank having a passageway to conduct products of combustion from said burner to said hollow structure and cause the same to contact both with said supporting means and with the wall of said tank.
10. In a combined incinerator and water 70 heater, a tank having an inner wall arranged to form a combustion chamber within said tank, a burner arranged adjacent to the lower end of said combustion chamber, a hollow structure extending about said upper end of and communicating with said combustion chamber and having an outlet for products of combustion, and a receptacle for material to be incinerated supported by said structure, extending into said opening and spaced from the inner wall of said tank to provide a passageway to conduct products of combustion from said burner to said hollow structure and to cause the same to come in contact with the wall of said tank and with said receptacle.
11. In a combined incinerator and water 75 heater, a tank having an inner wall arranged to form a combustion chamber within said tank, a burner arranged adjacent to the lower end of said combustion chamber, a hollow structure extending about the upper end of said combustion chamber and having an outlet for products of combustion, and a receptacle for material to be incinerated supported within said combustion chamber above said burner and spaced from said inner wall of said tank to form a relatively narrow passageway to conduct products of combustion from said burner to said hollow structure.
12. In a combined incinerator and water 80 heater, a tank having an inner wall arranged to form a combustion chamber within said tank, a burner supported adjacent to the lower end of said combustion chamber, a receptacle arranged within said combustion chamber and spaced from the inner wall of said tank to form a passageway for the products of combustion between said receptacle and the inner wall of said tank, and a structure arranged about the upper end of said combustion chamber and having an outlet for 85 said products of combustion.
13. In a combined incinerator and water heater, a tank having an inner wall arranged to form a combustion chamber within said tank, a burner supported adjacent to the 90
- 95
- 100
- 105
- 110
- 115
- 120
- 125
- 130

lower end of said combustion chamber, a receptacle arranged within said combustion chamber and spaced from the inner wall of said tank to form a passageway for the products of combustion between said receptacle and the inner wall of said tank, a structure arranged about the upper end of said combustion chamber and having an outlet for said products of combustion, and a water coil arranged about said receptacle and connected at its upper and lower ends with the upper and lower portions, respectively, of said tank.

In testimony whereof, I affix my signature
15 hereto.

WILLIAM C. EPSTEIN.
